UNITED STATES PATENT OFFICE.

ROLAND LEE GLADDEN, OF GADSDEN, ALABAMA.

LAMP-GLOBE HOLDER.

1,028,015.

Specification of Letters Patent.

Patented May 28, 1912.

Application filed May 5, 1911. Serial No. 625,164.

To all whom it may concern:

Be it known that I, ROLAND LEE GLADDEN, a citizen of the United States, residing at Gadsden, in the county of Etowah and State 5 of Alabama, have invented new and useful Improvements in Lamp-Globe Holders, of which the following is a specification.

This invention relates to lamp chimney holders, the object being to provide a simple 10 and inexpensive device of this character which may be adjusted to fit lamp chimneys of various sizes.

A further object of the invention is to provide a device of this character which 15 may be easily and quickly placed upon or removed from the lamp chimney, and which will effectively and reliably hold the same from accidental displacement.

With the above recited objects and others 20 of a similar nature in view, the invention consists in the construction, combination and arrangement of parts set forth in and falling within the scope of the appended claims.

25 In the accompanying drawings there has been illustrated a simple and preferred embodiment of the improvement, and in which drawings,—

Figure 1 is a side elevation of the improvement in applied position upon a lamp. Fig. 2 is a perspective view of the device detached, a portion of the casing being shown in section. Fig. 3 is a detail illustrating wire members provided with enlarged eyes to receive the loops of one of the spring members.

Like numerals of reference designate corresponding parts throughout.

In the drawings, the numeral 2 designates 40 the burner of a lamp, and 1 the usual outward projecting flange thereof.

My improved holder comprises essentially a pair of cylindrical casings designated respectively by the numerals 3 and 4. Each 45 of these casings is formed with an off-set hook 5 which is adapted to engage beneath the flange 2 of the burner. One of the casings 3 is further provided with a finger hold 6, the purpose of which will presently be 50 set forth. Positioned within each of the casings 3 and 4 is a helical spring 7. Each

of these springs have their lower extremities or coils off-set or projected as at 8, so as to provide means whereby the said springs cannot be removed from the casing 55 in one direction. Each of the springs has its opposite convolution extended to provide loops 9. The upper portions of each of the loops is coiled upon itself to provide the eyes 10.

60 The numerals 11 and 12 designate a pair of wire members which are adapted to surround the chimney of the lamp, and each of these members have their opposite ends formed with eyes 13 and 14 which are 65 adapted to engage with the eyes of the loops.

In applying the device, the wire members are arranged over the lamp chimney, and the casings are forced downwardly against 70 the pressure of the helical springs so that their hooks are brought into engagement beneath the flange of the burner. When it is desired to remove the holder from the lamp, the finger hold upon the casing 4 is 75 engaged so that the said casing is forced downwardly until its finger disengages the flange of the burner. This relieves the pressure of the spring within the opposite casing so that the device may be readily lifted 80 away from the lamp chimney.

Having thus fully described the said invention, what I claim is:—

1. A lamp chimney holder including a pair of casings, each having an engaging hook, a helical spring within each of the casings, each of the said springs having its lower end connected with the casing, and the upper end of each of the springs extended to provide a loop, the looped portion of each of the springs being bent to provide an eye, and a pair of oppositely arranged substantially semi-cylindrical members having their ends loosely connected with the eyes of the loops.

95 2. A lamp chimney holder comprising a pair of cylindrical casings, hook members upon the casings, a finger hold upon one of the casings, a helical spring within each of the casings, each of said springs having its 100 lower convolution off-set to contact with the casings and to prevent the removal of the

springs from the casings in one direction, the opposite convolution of each of the casings being extended to provide a loop, each of said loops having its upper portion coiled 5 to form an eye, and a pair of flexible elements having their extremities connected with the eyes of the loops, substantially as and for the purpose set forth.

In testimony whereof I affix my signature in presence of two witnesses.

ROLAND LEE GLADDEN.
